UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPE-WRITING MACHINE.

1,300,905.

Specification of Letters Patent. Patented Apr. 15, 1919.

Application filed August 7, 1917. Serial No. 184,820.

To all whom it may concern:

Be it known that I, JOHN A. WHERRY, a citizen of the United States, residing in New Orleans, in the parish of Orleans and State 5 of Louisiana, have invented certain new and useful Improvements in Type-Writing Machines, of which the following is a specification.

This invention relates to an improvement 10 in an attachment for typewriting machines, and more especially to a collating device for assembling work-sheets to be written on at different relative points. This case is an improvement on my application, No. 180,530, 15 filed July 14, 1917.

In the present case, the sheets are assembled face upwardly at the front of the platen on the collating portion of a paper carrier or collating frame, which is maintained in a position wrapped around the platen, and may be oscillated back and forth by rotating the platen.

For the purpose of positioning the assembled sheets on the platen, and carrying 25 them line by line in a normal typewriting operation, the frame may be provided with two series of studs, so that the work-sheets, which have corresponding openings in their side margins, may be impaled on the studs, 30 to properly position them relatively to each other and to the collating frame.

The work-sheets, after they have been placed on the collating frame, are preferably automatically fed around the platen 35 in a reverse line-space direction, by means of a spring connected by suitable mechanism to one end of the collating frame.

This automatic feed may be under the control of a finger-piece or releasing key connected to the line-space detent and the feed rolls. Under normal conditions, the automatic feeding of the platen may be prevented by the line-space detent and the pressure of the feed rolls.

45 Automatically-operated means, controlled by an adjustable stop on the collating frame, may be provided for limiting the reverse feeding movement of the collating frame with the work-sheets thereon to stop the rotation of the platen when the first printing line of the work-sheet reaches the printing point. This stop may be also effective to trip the finger-piece or release key, so as to

bring the feed rolls and detent into play when the work-sheets have been properly 55 positioned for printing.

The collating frame is flexible and is guided around the platen in a U-shaped path. It may have in addition to the spring connected to its one end for automatically 60 feeding it around the platen, another spring connected to its other end; the power of which is less than that of the first spring, and sufficient to keep the collating frame taut, but not to counteract the action of 65 said first spring.

The body portion of the collating frame may act as a backing for the work-sheets. This frame is detachable so that it may be 70 conveniently removed from the machine and replaced by another when the body portion becomes worn, or damaged by the types.

Other features and advantages will hereinafter appear.

In the accompanying drawings,

75 Figure 1 is a perspective view, showing the collating frame in a position to receive the work-sheets to be assembled.

Fig. 2 is a side elevation, with the parts in the position of Fig. 1.

Fig. 3 is a view similar to Fig. 2, except that the pressure feed-rolls and the line-space mechanism detent have been released, so as to permit the easy reversal of the collating frame and platen, for the purpose of 85 placing the work-sheets on the platen after having been collated.

Fig. 4 is a view similar to Figs. 2 and 3, partly in section, the collating frame having been moved downwardly at the front with a 90 reverse rotation of the platen, so as to place the assembled work-sheets on the platen, and the stop carried by the frame having tripped the pressure feed-rolls and line-space detent releasing mechanism. In this 95 position of the parts, the mechanism is ready for the initial line of typewriting.

Fig. 5 is a front view in elevation, partly broken away to show the underlying structure.

The platen 1 is mounted on the usual platen axle 2, which, in turn, is mounted in an inner carriage or platen frame 3. The platen 1 is rotated for a number of line spaces by the usual knobs 4 provided on the 105 end of the platen axle 2. It also may have

line-space movements by means of a line-space mechanism, indicated in general at 5, and including a line-space wheel 6. This line-space wheel is locked against accidental movement by means of a spring-pressed detent 7 in the form of a roll 8 mounted on a lever 9. This detent yieldingly holds the platen 1 at any line-space interval at which it is adjusted. To assist the platen 1 in feeding sheets, there are provided the usual pressure feed rolls 10 and 11, which are mounted on swinging frames 12 and 13, so as to be adjusted toward and from the platen 1.

15 Normally, the pressure feed rolls 10 and 11 are held in intimate contact with the platen 1 by means of springs (not shown). To release these pressure feed rolls, there is provided a finger-piece 14, which, when depressed, draws on a link 15 to rock a bell crank 16 secured to a shaft 17. The shaft 17 is provided with reduced portions 18 normally engaging their flat sides with arms 19 and 20, provided on the frames 12 and 13 carrying the pressure feed rolls 10 and 11. The rocking of the shaft 17 spreads the arms 19 and 20 apart, thereby withdrawing the pressure feed rolls 10 and 11 from engagement with the platen 1.

25 The pressure feed rolls 10 and 11 can be released from another point which also disengages the detent 7 from the line-space wheel 6. This includes a hand-lever 21, which, when depressed, pulls up on a link 22 to swing upwardly a platen release 23 engaging the detent 7. This release forces the roll 8 out of engagement with the teeth of the line-space wheel 6. The release 23 is connected by a link 24 to an arm 25 on the rock shaft 17. Thus, the hand-lever 21 can release the detent 7, and at the same time rock the shaft 17 to release the pressure feed rolls 10 and 11. The reduced portions 18 on the shaft 17 act to lock the feed rolls in their released position when they are operated from the finger-piece 14 or the hand-lever 21. This also locks the detent 7 in its release position, until either the hand-lever 21 or the finger-piece 14 is returned to its normal position.

30 For the purpose of assembling sheets at different relative positions with respect to each other, so that the writing may be reproduced on several sheets and on the proper lines on different sheets, there is provided a collating frame or paper-carrier 26, which normally extends around the platen 1 between the platen and the pressure feed-rolls 10 and 11. This frame is made of a sheet of flexible material, which has attached thereto a pair of collating strips 27, arranged to extend around the platen at opposite ends thereof. These collating strips 27 are provided with paper-holding means

35 or collating studs 28 upon which the work-

sheets 27^a may be impaled to adjust them relatively to each other and relatively to the collating frame 26. The work-sheets may have perforations on either side margin, or, if wide enough to stretch across the frame, on both side margins, so that they can be placed over the studs 28. It will be noted that the strips 27 extend around the platen 1 in such a manner that the studs 28 face to the front, and are located at that end of the strip 27 which extends upwardly from the front of the platen 1. This enables the work-sheets 27^a to be impaled on the studs 28 facing front with their leading edges uppermost.

40 Normally, a driver in the form of a spring 29 tends to hold or withdraw the collating frame 26 to its starting position shown in Figs. 4 and 5. This spring 29 is connected to levers 30 and 31 forming part of an expanding device 32 having a lazy tongs motion. This expanding device is slidingly pivoted at 33 to a guiding and supporting plate 34, which extends upwardly from the rear of the platen frame 3. Floating pivots 35 of the expanding device 32 are yieldingly guided in a slot 36 provided in the plate 34. The expanding device 32 is secured by pin-and-slot connections 37 and 38 to a cross-bar 39 connected by a stud 40, extending through the slot 36 to a second cross-bar 41, located in front of the plate 34. The rear end of the collating frame 26 is caught onto the cross-bar 41 by means of a pair of hooks 42 provided on the cross-bar 41, and extending through openings 43 provided on the tail end of the collating frame 26. The spring 29, through the lazy tongs 32 and the cross-bars 39 and 41, normally exerts a pull on the tail end of the collating frame 26, so as to hold the latter taut.

45 The action of the spring 29 is opposed by a second spring 43^a, which tends to extend a second expanding device 44 in a manner similar to the first expanding device 32. The second expanding device 44 is connected to the leading edge of the collating frame 26. This connection includes a cross-bar 45, located in back of a supporting and guiding plate 46, extending up from the front side of the platen 1 and supported by the platen frame 3. The guiding plate 46 is provided with a slot 47, through which extends the moving pivots of the expanding device 44. The cross-bar 45 is also connected to this slot 47 through a front cross-bar 48 by means of a pin 49. The cross-bar 48 is located in front of the plate 46, and is provided with hooks 50 to extend through openings 51 in the leading edge of the collating frame 26, and thereby support the collating frame. Inasmuch as the first spring-actuated expanding device draws on the tail end of the collating frame 26, and the second spring-actuated expanding device draws on the

125

130

leading edge of the collating frame 26, the frame will be held tight on the platen 1, and the free ends thereof, which extend from the platen, will be held taut.

5 For the purpose of maintaining the collating frame always in the same relative line-space positions with respect to the platen, or in other words to prevent slippage, as the collating frame moves back and forth with the rotation of the platen, a pin-and-sprocket arrangement is provided. This includes pins 52 located on both ends of the platen 1 in a circular series, so as to form sprocket wheels, which engage in perforations 53 provided on both sides of the collating frame 26. In this way, the position of the collating frame will be justified and the line-space intervals always maintained in corresponding relation with respect to the platen 1.

After the sheets are assembled on the collating frame the platen is revolved backwardly or reversely to carry them around to their starting position. To enable this reversal to be easily done, the pressure feed-rolls 10 and 11 are released, and the detent 7 is withdrawn from engagement with the line-space wheel 6 by an operation of either the finger-piece 14 or the hand-lever 21. The spring or driver 29 now becomes effective to feed the collating frame backwardly to introduce the work-sheets into the machine. The releasing mechanism is automatically tripped when the collating frame reaches a position corresponding to the proper placement of the work-sheets on the platen after they have been assembled. This is done automatically by an adjustable stop or trip 54 provided on the collating frame 26. The trip 54 may be secured in any one of a number of holes 55, so as to vary the instant of its action, and thus make its action correspond with the particular requirements of the work being collated. The trip 54 travels around rearwardly with the collating frame 26 until it comes into engagement with an arm 56 on a bell crank 57. Then the trip 54 will rock the bell crank 57, so as to force an arm 58 on the bell crank 50 against one of the arms of the hand-lever 21. The hand-lever 21 is rocked from the position shown in Fig. 3 to the position shown in Fig. 4, thereby restoring the detent 7 and the pressure feed-rolls 10 and 11. After this latter action has taken place, the collating frame is positively arrested by the stop 54 coöperating with the arm 56.

When a new piece of work is to be done, the parts are adjusted to the position shown in Figs. 1 and 2, to enable the work-sheets to be easily collated. The work-sheets 27^a, with the interleaved carbon sheets, are then collated by being impaled on the studs 28 in the various relative positions desired, so as to have the desired lines thereon in regis-

ter with each other, although these lines may not be at the same relative positions on the several sheets. After the sheets have been assembled or collated, the release key 21 is actuated, thus rendering the spring 29 effective to reversely rotate the platen, and it will carry the collated work-sheets, bottom edge first, down around the platen until the trip 54 comes into engagement with the arm 56 and bell crank 57. Then the trip 54 will first unlock the releasing mechanism, enabling the detent 7 and the pressure feed-rolls 10 and 11 to return to their active positions. The trip 54 thus limits the return movement of the collating frame 26 by causing the detent to arrest the reverse rotation of the platen 1, so that the initial position of the collated work-sheets for the first line of writing is automatically determined. This may be changed as desired to suit the character of work, by adjusting the trip 54 in any one of the openings 55. When so positioned, the work may be written line by line until completed, the frame 26 traveling in synchronism with the platen 1, inasmuch as it is positively geared thereto by means of the pin-and-sprocket arrangement 52, 53. The rear support 34 will keep any work-sheets from dropping off the studs 28, especially any that extend only part way across the platen. When the work is completed, it can be detached from the studs 28 and a new set of sheets collated or assembled on the collating frame 26. During the back and forth movement of the frame 26, the springs are maintained taut and the work-sheets held smooth in all positions of the latter.

The collating frame may be readily detached from the machine and replaced by another having its rows of collating studs spaced differently apart, as it may sometimes be desired to collate sheets with different distances between rows of perforations or collating holes. The collating frame is detachably mounted, so that it can be conveniently replaced since it becomes worn by the frequent hammering of the type-bars, if it extends across the platen and serves as a backing for the work-sheets.

Variations may be resorted to within the scope of the invention, and portions of the improvements may be used without others.

Having thus described my invention, I claim:

1. The combination with a platen, of a flexible collating frame wrapped around said platen, and oppositely-acting springs connected to the ends of said frame for maintaining said collating frame taut and smooth on said platen.

2. The combination with a platen, of a collating frame wrapped around said platen, an expanding device connected to the leading edge of said collating frame, a spring

- for operating said expanding device, and means for opposing the action of said spring so as to maintain said frame taut on said platen.
5. 3. The combination with a platen, of a flexible collating frame wrapped around said platen, guiding means for the ends of said frame, and spring-operated means for maintaining said frame smooth on said platen.
10. 4. The combination with a platen, of a mechanism coöperating with said platen to feed and manipulate work-sheets around said platen, a collating frame coöperating with said platen to manipulate said work-sheets, releasing means for said mechanism, enabling the proper placement of said work-sheets on said platen, by a reverse rotation of said platen, and a trip passing from the front of said platen to the rear thereof for 20 operating said releasing means to bring said mechanism into play.
5. The combination with a platen, of a collating frame wrapped around said platen for carrying assembled work-sheets in 25 proper relative position around said platen, line-space mechanism for said platen, pressure-feed rolls for coöperating with said platen to assist in manipulating work-sheets on said collating frame on said platen, a de- 30 tent for yieldingly holding said line-space mechanism at line-space intervals, releasing means for both said detent and said pressure-feed rolls, and a trip passing by a reverse rotation of said platen from a position in 35 front of said platen to a limiting position in the rear of said platen to act to operate said releasing means, so as to bring said detent and said pressure-feed rolls into play.
6. The combination with a platen, of an 40 open-ended flexible collating frame wrapped around said platen, a guide for the tail end of said collating frame, extending upwardly from the rear of said platen, and a guide for the leading edge of said collating frame, ex- 45 tending upwardly from the front of said platen.
7. The combination with a platen, of a collating frame wrapped around said platen, and individual guiding means for the free 50 ends of said collating frame.
8. The combination with a platen, of a collating frame wrapped around said platen, individual guiding means for the free ends of said collating frame, and spring mecha- 55 nism individual to each of said free ends, acting to hold said collating frame taut.
9. The combination with a platen, of a flexible collating frame wrapped around said platen, the collating portion of said collat- 60 ing frame being arranged at the front of said platen, means for automatically feed- 65 ing said collating frame in a reverse line-space direction, and means for rendering said automatic feeding means effective.
65. 10. The combination with a platen, of a flexible collating frame wrapped around said platen, the collating portion of said collating frame being arranged at the front of said platen, means for automatically feed- 70 ing said collating frame in a reverse line-space direction, means for rendering said automatic feeding means effective, and a stop for limiting the movement of said collating frame in the reverse line-space direction.
11. The combination with a platen, of a flexible collating frame wrapped around said platen, the collating portion of said collating frame being arranged at the front of said platen, a platen release, means for automatically feeding said collating frame in a re- 75 verse line-space direction, means for rendering said automatic feeding means effective, and means for automatically stopping the collating frame in the reverse line-space direction and for rendering the platen release 80 effective.
12. The combination with a platen, of a flexible collating frame wrapped around said platen, the collating portion of said collating frame being arranged at the front of said platen, means for automatically feeding said collating frame in a reverse line-space direction, means for rendering said automatic feeding means effective, an 85 adjustable member on said collating frame, a platen release, feed rolls, and means for actuating said platen release and for throwing off said feed rolls, to render said automatic means effective, said adjustable member being effective to stop the collating 90 frame after it has been moved through a predetermined distance, said adjustable member being also effective to render said platen release and feed rolls effective.
13. The combination with a platen, of a collating belt adapted to be curved around the platen, a supporting plate above and in front of the platen upon which said belt may lie, said supporting plate adapted to support a work-sheet while being adjusted 100 on the belt, and means adapted to be made effective to cause said belt to automatically carry the work-sheet thereon to a writing position.
14. In a typewriting machine, the combination of a flexible collating belt forming a paper-carrier, a platen, line-space mechanism therefor including a detent, a supporting plate, in front of and above the platen, adapted to support a work-sheet while being 110 adjusted on the belt, a device for drawing the belt to carry the work-sheet thereon to the printing line, and means for releasing the detent to permit said device to become effective.
15. The combination of a flexible paper-carrier, line-space mechanism therefor, a backing for said paper-carrier, means for guiding said paper carrier over said back- 120 ing, a detent, driving means, means for re- 125

- leasing said detent to render said driving means effective on said paper-carrier, and means for automatically stopping said paper-carrier in a predetermined position.
- 5 16. The combination of a flexible paper-carrier, line-space mechanism therefor, a backing for said paper-carrier, means for guiding said paper-carrier over said backing, a detent, driving means, means for releasing said detent to render said driving means effective on said paper-carrier, an adjustable stop on said paper-carrier, and means engaged by said adjustable stop for rendering said detent effective.
- 10 17. The combination of a paper-carrier including holding means, line-spacing mechanism, a backing for said paper-carrier, means for guiding said paper-carrier around said backing, feed rolls coöoperating with said paper-carrier, driving means, a detent, means for releasing said detent and said feed rolls, to render said driving means effective on said paper-carrier, an adjustable stop for said flexible paper-carrier, and
- 20 25 means coöoperating with said stop for rendering said detent and said feed rolls effective.
18. The combination of a flexible paper-carrier, line-spacing mechanism for said paper-carrier, means associated with said paper-carrier, which tends to draw it in a line-spacing direction to hold said carrier taut, means coöoperating with said paper-carrier to feed it in a reverse line-spacing direction, a detent for said paper-carrier, a release for said detent, and means for automatically rendering said detent effective.
- 30 35 19. The combination with a belt forming a flexible paper-carrier, of a roller platen, a support for said carrier in front of the platen, over which a sheet may be adjusted on the carrier, driving means to carry the carrier backward, means for releasing said detent to render said driving means effective on the carrier, and means for automatically stopping said carrier and platen in a predetermined position.
- 40 45 20. The combination with a belt forming a flexible paper-carrier, of a support for said carrier, over which a sheet may be adjusted on the carrier, a roller platen, a detent for the platen, driving means to carry the carrier backward, means for releasing said detent to render said driving means effective on the carrier, an adjustable stop on said carrier, and means adapted to be engaged by said stop for rendering the detent effective.
- 50 55 21. The combination of a flexible paper-carrier, line-space mechanism therefor, a roller connected to said line-space mechanism, feed rolls, said paper-carrier being fed between said roller and said feed rolls, driving means, a detent, means for releasing said detent and said feed rolls to render said
- driving means effective to drive said paper-carrier, and means for automatically rendering said detent and said feed rolls effective.
22. The combination with a platen, of a flexible paper-carrier wrapped around said platen, said paper-carrier having a work-sheet receiving portion arranged at the front of said platen, and means for guiding said paper-carrier, said paper-carrier being detachably connected to said guiding means.
- 70 75 23. The combination with a paper-carrier including collating studs, of a platen, around which said carrier passes, line-spacing mechanism, feed rolls, driving means for the carrier, a detent for the platen, means for releasing said detent and feed rolls to enable the driving means to carry the carrier backwardly around the platen, an adjustable stop for the carrier, and means adapted to be operated by the stop to make the detent effective.
- 80 85 24. The combination with a platen, of a belt adapted to be curved around the platen, collating studs on the belt, a support in front of the platen, along which the belt may extend, and which is adapted to support work-sheets while being adjusted on the studs, a support behind the platen, along which the belt is adapted to be drawn, and which is adapted to support the free margin of work-sheets, and a device to which the belt is adapted to be hooked to tension it along a support.
- 90 95 25. The combination with a platen, of a belt adapted to be curved around the platen, collating studs on the belt, a support in front of the platen, along which the belt may extend, and which is adapted to support work-sheets while being adjusted on the studs, a support behind the platen, along which the belt is adapted to be drawn, and which is adapted to support the free margin of work-sheets, and a finger-piece operable to cause the belt to carry the work-sheets to the latter support.
- 100 105 110 26. The combination of a flexible paper-carrier, and two expanding devices associated therewith, one expanding device being effective to feed said paper-carrier, the other device being effective to keep said paper-carrier taut.
- 115 27. The combination of a flexible paper-carrier, line-space mechanism therefor, an expanding device having a lazy tongs movement for feeding said carrier in a reverse line-space direction, and a second expanding device having a lazy tongs movement for maintaining the paper-carrier taut while it is moving in either a line-space or a reverse line-space direction.
- 120 125 28. The combination with a platen, of a belt adapted to be curved around the platen, collating studs on the belt, a support in front of the platen, along which the belt may extend, and which is adapted to support work-
- 130

sheets while being adjusted on the studs, a support behind the platen, along which the belt is adapted to be drawn, and which is adapted to support the free margin of work-sheets, a finger-piece operable to cause the belt to carry the work-sheets to the latter support, and an adjustable stop adapted to

arrest the belt when a work-sheet thereon arrives at the proper printing line.
